UNITED STATES PATENT OFFICE.

JACOB KERSTEN, OF KALAMAZOO, MICHIGAN.

RADIO LOUD-SPEAKER CONSTRUCTION.

Application filed March 28, 1927. Serial No. 178,852.

This invention relates to a radio loud speaker construction and is particularly concerned with the housing which encloses an amplifying horn to which the loud speaker unit is connected. The invention is directed to the structure of the housing and the method followed in producing the two parts or halves of said housing.

It is a primary object and purpose of the present invention to provide a housing for amplifying horns made of paper and papier mâché, and to strengthen and reinforce the same so that it will be durable in service and so that one side or half of the housing may be provided with a large number of openings through which the sound escapes without fear of the parts left between said openings breaking or disintegrating. More specifically, the housing members made of paper and papier mâché are reinforced around their edges by embedded wire rings and are reinforced at their outer sides by fabric cemented thereon, which fabric greatly strengthens the housing parts and makes it possible to saw desired openings in accordance with any particular design without the material breaking or crumbling, while said fabric at the outer side of the housing members is particularly useful in the application and retention of a finish for said housing.

To these ends as well as many others, I have made the invention and have devised a practical method for the same, understanding of which will be had from the following description taken in connection with the accompanying drawings, in which,

Fig. 1 is a front elevation of the complete assembled housing.

Fig. 2 is a central vertical section therethrough.

Fig. 3 is a vertical section through the mould used in constructing each of the halves or parts of the housing.

Figs. 4, 5 and 6 are fragmentary enlarged vertical sections illustrating different steps of the method followed in constructing each housing part, and

Fig. 7 is a fragmentary vertical section showing the application of the fabric outer member to each housing part after it has been removed from the mould.

Like reference characters refer to like parts in the different figures of the drawings.

The mould used comprises a block 1 in the upper side of which a large conical recess or depression 2 is made which at its upper edges joins with a vertical ledge 3 made in the moulding block 1. This ledge is of comparatively shallow depth and is set inward from the outer edges of the block so that a horizontal face 4 is provided at the upper side of the block outside of the ledge 3.

In the mould thus formed each half of the housing is made. In the first instance, two sheets of paper 5 and 6 are laid in the mould and are fitted to the ledge 3 and extend outwardly over the face 4 of the mould. These sheets of paper in practice are known as rosin paper and are cemented together by a suitable glue paste. After the two sheets 5 and 6 have been laid in the mould, as shown in Fig. 4, a circular ring 7 made of wire is laid in the mould and it is of such size that it engages against the sheet 6 of the paper directly opposite the ledge 3.

The succeeding step of the method followed is to lay in and cement two sheets 8 and 9 of papier mâché. These sheets are thicker than the rosin sheets 5 and 6 used and are less tough and porous. The sheets 8 and 9 when cemented in place have their edges coming to the inner sides of the wire ring 7 and are thick enough that the two together are substantially equal to the diameter of the wire used.

The final step of the method followed in the mould is to cement two additional sheets 10 and 11 of tough rosin paper above the sheet 9 of papier mâché, the same extending over the ring 7 and fitting against the sheet 6 which extends outwardly over the upper horizontal sheet 5 of the construction.

This completes the formation of a half of the housing in the mould. It is removed from the mould and dried, after which a piece of knitted fabric 12 is stretched over the outer side of the housing member formed, as shown in Fig. 7, being glued to the outer sheet of paper 5 which was the first sheet laid in the mould. The fabric adds considerable strength to the structure made, and particularly it prevents breaking

of the edges when the housing parts are subjected to sawing operations as will now be described.

When each half of the housing has been completed as described it consists of a conical body 14 from which an annular lip 15 projects. Both parts of the housing are sawed so as to remove the rough edges of the lips 15. The two halves of the housing are joined together by a tubular ring 16 slotted at its inner side which clamps against the abutting lips 15 of the housing, as shown in Fig. 2. Ring 16 is continuously around the housing except at the lower side 15 where there is a gap, and certain portions of the housing are sawed away to leave an opening 17 through which the lower end or neck of the amplifying horn passes. The front side of the housing is sawed on a band saw so as to make a large number of openings 18 which are cut to make any suitable artistic design. Without the fabric covering 12 it would be impossible to cut these openings 18 for the reason that the narrow portions left between the openings would be too weak, would easily break and particularly at the edges, would crumble. But by use of the fabric outer side such crumpling and breaking is completely eliminated.

In addition, the outer side of both parts of the housing necessarily must be finished to present a good appearance and the fabric stretched over the outer sides of said housing parts is especially effective to receive and retain a filler, varnish or other finish which may be applied.

The construction of the parts of an amplifying horn housing described and the method followed is one which has proved very useful and practical. It results in economy of manufacture while the use of paper and papier mâché is very desirable in devices of this kind by reason of the acoustic properties present which eliminate metallic sounds. The invention is defined in the appended claims and is to be considered comprehensive of all forms of structure coming within their scope.

I claim:

1. A housing for amplifying horns comprising, two conical shaped parts having their base edge portions abutting, means for securing the edge portions of said parts together, each of said parts being of paper and covered at its outer sides with fabric cemented thereto.

2. In a housing member for use in producing a housing to enclose an amplifying horn comprising, a conical shaped body having an annular lip extending outwardly from the edges of said body, said body and lip being formed of paper material, and fabric cemented to the outer side of said body and lip.

3. An article of manufacture comprising,

a conical shaped body having an integral annular lip extending from the base edges of said body, and a wire ring embedded in said article substantially at the juncture of the body and lip.

4. An article of manufacture comprising, a conical shaped body having an annular lip projecting from the base edges thereof, said body including at its inner side sheets of paper cemented together and extending outwardly to the outer edges of said lip, papier mâché located over and cemented to the inner of said paper sheets extending substantially to the juncture of the lip and body, a wire ring located around the edges of said papier mâché and additional thicknesses of paper cemented over said papier mâché and extending over and beyond said ring and cemented to the first mentioned sheets of paper to make said lip.

5. A construction containing the elements in combination defined in claim 4, and a covering of stretchable fabric stretched over the outer side of the body and lip cemented thereto and extending to the edges of said lip.

6. An article of the class described comprising, a conical body having an annular lip projecting from the base edges of said body, said body comprising inner and outer strata of relatively tough paper, said strata extending to the edges of said lip and being cemented together, an inner filler of papier mâché or the like extending substantially to the juncture of said body and lip, and a metal reinforcing ring disposed between the outer and inner strata of tough paper and around the edges of said inner filler, substantially as described.

7. A housing for amplifying horns comprising, two members, each forming a half of the housing and each being of recessed form having their base edges located against each other and secured together, each of said members at its lower side having a portion cut away to make an opening in the lower side of the housing and one side of said housing having a plurality of openings cut therethrough in accordance with any preferred design, each of said members having an inner body of paper material and an outer covering of elastic fabric stretched over and cemented to the same.

8. The method of manufacturing a housing member for an amplifying horn which consists in providing a recessed mould, fitting inner strata of tough paper into said mould and extending the edges thereof beyond the edges of said depression, laying a metal reinforcing ring against said paper substantially at the edges of the depression of the mould, fitting in a filler of paper material over said first strata within said ring and substantially of a thickness equal to the diameter of the ring and then laying strata

of tough paper over said filler and over said ring and extending the edges to overlap the edge portions of the first strata, and cementing all of the paper strata and material 5 together.

9. The process of manufacture which consists of the steps defined in claim 8 and further in removing the article formed from

the mould, drying the same and then cementing an outer covering of stretchable fabric 10 against the first sheet of paper placed in the mould, drawing and stretching the fabric over the article with its edges extending to the edges of said first paper sheet.

In testimony whereof I affix my signature.
JACOB KERSTEN.
